S. A. SULECIO

NECKTIE HOLDER

Original Filed March 16, 1921

INVENTOR.

Salvador Aquilar Sulecio

BY
Carlos P. Griffin
ATTORNEY.

UNITED STATES PATENT OFFICE.

SALVADOR AGUILAR SULECIO, OF SAN FRANCISCO, CALIFORNIA.

NECKTIE HOLDER.

Application filed March 16, 1921, Serial No. 452,828. Renewed October 22, 1923.

To all whom it may concern:

Be it known that I, SALVADOR AGUILAR SULECIO, a citizen of Guatemala, residing at San Francisco, in the county of San Francisco, State of California, have invented new and useful Necktie Holders, of which the following is a specification in such full and clear terms as will enable those skilled in the art to construct and use the same.

10 This invention relates to necktie holders, one object of which is to provide means for holding a tie in a neat attractive knot, while at the same time enabling the user to vary the position of the fold without injury to 15 the tie.

Another object of the holder is to provide means whereby the tie may be held in place on one of the common high turn down collars without being passed entirely around 20 the collar, thereby dispensing with the annoying feature of having to pull the tie around the collar to produce the proper kind of a knot.

Another object of the invention is to produce 25 a holder which will reduce the wear on the collar and which will be capable of holding the ends of the collar in a neat position.

Another object of the invention is to provide 30 means to secure the tie to the holder, which will permit the tie to be moved to several positions to prevent the fold formed in the tie from becoming a permanent crease, without removing said securing 35 means.

Another object of the invention is to provide 40 a cross strap for the tie, which is capable of being reversed, to turn the worn or faded side in, thereby increasing the usefulness of the tie.

It will be understood by those skilled in the art that any metal may be used to produce the frame of the holder and that the frame may be provided with the buttons 45 to pass through the holes in the collar wings.

In the drawings in which the same reference numeral is applied to the same portions throughout the several views, but of 50 which there may be modifications,

Fig. 1 is a front view of the collar with the tie in place on the holder.

Fig. 2 is a front elevation of the holder.

Fig. 3 is a view of the holder in plan.

Fig. 4 is a view of the cross strip of the 55 tie.

Fig. 5 is a view showing the shape of tie used.

Fig. 6 is a front elevation of the tie and modified holder as it appears when used on a collar without button holes in the tabs. 60

Fig. 7 is a front view of the modified form of holder.

Fig. 8 is a plan view of the holder shown in Fig. 7 and

Fig. 9 is a perspective view of a portion 65 of the holder and collar.

The numeral 1 indicates the collar which has the usual inner buttonholes to secure it to the shirtband, and in addition it has buttonholes 2 and 3 in the outside wings. The 70 tie is indicated at 4 and it has a cross-piece 5 which is connected by three snap posts 7, 8 and 9 to its opposite end by the three eyelets 10, 11 and 12.

The tie is slightly larger than the central 75 portion of the usual four-in-hand tie and the cross-piece is of the same width as the cross-piece in the usual four-in-hand tie, although sizes are not material to the invention.

The holder in each instance consists of a 80 single length of a suitable wire 13. The wire is bent to produce two laterally extending wings 14 and 15 curved to fit the collar. The wire is then bent downwardly at each 85 end (see 16 and 17), to produce a support of substantially the same length as the width of the cross-piece 5.

The portions 16 and 17 of the frame have 90 their ends outwardly bent as shown at 18, 19 and are provided with small buttons 20, 21, which are passed through the buttonholes 2 and 3 when in use.

The tie is folded once and then laid over the top of the frame, the cross-piece is then 95 passed once around the tie, and the parts 16, 17, whereupon it is secured in place with the snaps. When thus arranged, the tie may be slipped up or down as may be desired, to prevent undue wear in any one place, or if it is desired the cross-piece may be removed 100 and the tie may be reversed in position. When the tie is used, it has the parts 14 and 15 slipped between the folds of the collar and the buttons are pushed through the buttonholes. 105

In the form of the invention shown, in Figures 6 to 9, the wire 13 has the side members 25, 26 exactly the same as the side members 14, 15, but the depending members 27, 28 terminate in two upwardly extending flat 110

22
 coils 29, 30; the wire of said coils being stiff enough to tightly engage the inner collar band when the tie is worn, and dispense with the use of the buttonholes in the outer wings 5 of the collar. In this form of the invention, the tie is secured to the holder in the same way as in the previous form, and the holder is simply pushed up in place with the coils 29, 30 back of the inner band of the collar, 10 the holder being retained by friction.

It will be apparent that the holder is completely concealed in both instances, the tie giving the appearance of the usual four-in-hand knot.

15 Another advantage of this necktie holder is that it may be used without handling the collar as much as is ordinarily necessary, and thereby keeps the collar cleaner.

Another advantage of this invention lies 20 in the fact that it keeps the necktie in an elegant and perfect form at all times, avoiding the usual wrinkling.

The necktie is also formed of two smaller pieces than the usual four-in-hand, thereby 25 being more economical.

Another advantage of this necktie holder is that it prevents the collar button and inside band of the collar from being seen above the tie.

It will be understood that the holder may 30 be made in different sizes as may be required for collars of different heights.

Having thus described my invention, what I claim as new and desire to secure by Letters Patent of the United States is as 35 follows:

1. An article of neckwear comprising a frame having means to secure it to a collar and a necktie consisting of two flat portions, one of which is hung on the frame, and the 40 other of which surrounds the frame and tie.

2. A necktie and holder comprising a supporting frame having means to connect it to a collar, a reversible necktie folded over the frame and depending therefrom, and a reversible detachable band surrounding the tie and frame to give the appearance of a knot. 45

3. A necktie and holder comprising a supporting frame, means to detachably engage the frame with a collar, a reversible necktie folded over the frame and depending therefrom, a separable band surrounding the tie and frame, and snaps to secure the ends of 50 said band together.

In testimony whereof I have hereunto set 55 my hand this 11th day of March, A. D. 1921.

SALVADOR AGUILAR SULECIO.
